CLAIM

The ornamental design for a portable weld controller, as shown and described.

DESCRIPTION

FIG. 1 is a front perspective view of a portable weld controller showing our new design;

FIG. 2 is a rear perspective view thereof;

FIG. 3 is a rear perspective view thereof;

FIG. 4 is a rear perspective view thereof;

FIG. 5 is a rear perspective view thereof;

FIG. 6 is a front elevation view thereof;

FIG. 7 is a rear elevation view thereof;

FIG. 8 is a right side elevation view thereof;

FIG. 9 is a left side elevation view thereof;

FIG. 10 is a top plan view thereof; and,

FIG. 11 is a bottom plan view thereof.

The broken lines in the drawings depict unclaimed environmental subject matter.
